Attorney

Attorney

UNITED STATES PATENT OFFICE.

MARY BORGES, OF NEW BEDFORD, MASSACHUSETTS.

SHADE AND CURTAIN FIXTURE.

Application filed November 10, 1921. Serial No. 514,219.

To all whom it may concern:

Be it known that I, MARY BORGES, a citizen of the Republic of Portugal, and a resident of New Bedford, in the county of Bristol and State of Massachusetts, have invented certain new and useful Improvements in Shade and Curtain Fixtures, of which the following is a specification.

This invention appertains to improvements in shade and curtain fixtures of that type which has a pair of supports for brackets that are adapted to maintain shade rollers, the supports also maintaining means for connecting therewith a bowed or arched curtain rod, the invention being made up to provide longitudinally adjustable brackets for shade rollers, and a pair of curtain rod holders which are attached to supports the parts being of such construction that the shade rollers and the curtain pole may be maintained in different horizontal planes.

A shade and curtain fixture made in accord with my invention consists of complementary supports each support being shaped to have an outstanding front portion which has therethrough a longitudinal slot, and integral ends which are apertured for the passage of attaching means by which the supports are secured to a sash or window frame, the supports having associated therewith brackets for shade rollers and curtain rod supports which extend upward from the end portions of the supports for the brackets, the curtain rod supports having their upper ends shaped to provide a crotch and having upstanding members or tines that are shaped to bear against the window frame or against the curtain pole or rod to hold the same when arched in a horizontal position, as will be hereinafter set forth.

Objects of my invention are to provide simple and efficient means for maintaining an arched curtain pole or lambrequin rod in horizontal position and projecting from the upper portion of the window frame, and to associate with the support therefor brackets for shade rollers, the brackets being adjustable upon the supports and of such construction as to maintain a shade

roller below the plane of the curtain pole or lambrequin rod.

A further object of my invention is to provide the supports that maintain a curtain pole and a shade roller with means that depend from the supports to engage with a second shade roller, which may be maintained thereby within the side pieces of the window frame, as will be hereinafter set forth.

In the accompanying drawings Figure 1 is a front elevation of one of the shade and curtain fixtures which embodies my invention. Fig. 2 is a plan view. Fig. 3 is a detail perspective view of one of the brackets, which shows the same attached to a support. Fig. 4 is a side elevation of one of the curtain pole supports. Fig. 5 is a front elevation of the curtain pole support shown by Fig. 4. Fig. 6 is a front elevation of a modified form of my invention, the tines of the fork being shown as equi-distant from the stem of the curtain-pole support. Fig. 7 is an end elevation of the structure shown by Fig. 6, and Fig. 8 is a plan view thereof.

In the principal views of the drawings I have shown only one end portion of the shade and curtain fixtures, it being understood that the parts will be substantially duplicated on the opposite side of the window frame.

Referring to the drawings, in which like numerals are applied to like parts, 10 indicates the front upper portion of a window frame and 11 the portion or sides between which are located the sash-frame, and to the upper portion of the window frame supports 12 will be secured. The supports 12, may be made from a strip of metal or they may be cast, their shape being such as to provide an outstanding central portion through which is formed a slot 13, beyond which the end portions of the supports extend inward and then outward parallel to the slotted front portion. The terminals of the supports 12 are apertured for screws used to attach the supports to the window frame and one of the terminals of the supports is shaped to provide a vertical

socket 14, or equivalent means for associating with the support a curtain rod carrier, as 15.

The curtain rod carriers 15 are bifurcated 5 at their upper portions and preferably one of the tines will be in line with the stem, the other tine being out of line with the stem, the lower end of the stem being tapered and having a shoulder, as shown in 10 Fig. 5. The stem may be flattened and intermediately bent so that the tines will have a tendency to press against the face of the window frame when the opposite end is seated in the socket 14. The curtain rod 15 carriers or members 15, when of the form shown may be used to carry a curtain pole 16 having curved ends to which are secured plates 17 or flanges which bear against the window frame and serve with the pressure 20 of the tines of the fork against the plates or flanges to maintain the arched pole in a horizontal position across the upper part of the window frame. When the members 15 are not required to carry an arched pole 25 they may be turned to position one of the tines of the fork outward, and when so positioned will maintain a straight curtain pole. A pair of curtains or lambrequins in practice are attached to rings on the pole, 30 and when arched poles are used the curtains or lambrequins and the supporting rings may be slid to occupy a position adjacent to the ends of the pole. The pole supports 15 instead of having their lower ends shaped 35 to be inserted in sockets in the supports 12, may be fastened otherwise thereto, for instance by screws as indicated on Fig. 6, of the drawings.

The shade roll is maintained by brackets 40 18, each of which is preferably made from sheet metal and of such form or shape as to provide a rear transverse portion 19 and side members 20 and 21 which extend forward, in use, and are of different lengths the same 45 having at equal distances from the rear portion slits or open ended slots 22, and the longer side member 21 has formed there-in either a perforation or a recess as 23 to receive a stud of the shade roll. The 50 rear wall of the bracket 18 has a threaded aperture for a bolt 24, the head of which bears upon the support 12 adjacent to the walls of the slot 13, said bolt clamping the bracket securely to the support and 55 providing for adjustment thereon to suit the length of the shade roller carried by the brackets.

As shown by Figures 6, 7 and 8 of the drawings, the inner ends of the supports, 60 when in place, may have secured thereto depending members 25, which have at their lower ends inwardly extending portions 26, with recesses in their upper edges, indicated by 27, for the reception of studs on 65 shade rollers, such rollers when used being

between the inner side walls of the window frame. The depending shade roller carriers 25, may be of such length as to locate a curtain roll about opposite the meeting rails of the sashes, and when of a length 70 to maintain the shade roll in such position half length shades may be used, otherwise the depending shade roll carriers may be short, and in neither instance will the shade rollers interfere as they will be out 75 of vertical alignment with each other.

The shade rolls when a pair are used for one window admit of the use of one full length shade and one of a half length, or two of full length as desired and the invention 80 also provides for maintaining either an arched or a straight curtain pole, for the support of a pair of curtains.

The shade and curtain fixture herein described and illustrated is simple in construction and is readily attachable for use, the supporting members are not connected as the supports are usually secured to the corner blocks of the window frame, and the resilient curtain pole support in connection with a bowed curtain pole having flanges or plates at its ends holds the pole securely in place, and such support may also be used to carry a straight pole. 85 90

I am aware that it is not broadly new 95 to have curtain fixtures of a construction adapted to support in place curtain poles and curtain rolls, and to provide for a variety of adjustments of the same, and I make no broad claim thereto, nor do I restrict my invention to such changes or modifications as may fall within the scope 100 of my invention as pointed out in the following claims.

I claim:

1. A shade and curtain fixture, comprising a support having end portions with apertures therethrough and an outstanding intermediate portion provided with a longitudinal slot, a bracket having a transverse rear portion through which is formed a threaded aperture and side members with open-ended and aligned slits for engagement with the outstanding portion of the support and a bolt for fixedly connecting the bracket with the support. 105 110 115

2. A shade and curtain fixture, comprising a support for attachment to a window frame provided at one end with a vertical socket, a bracket for a shade roller which is adjustably associated with the support, a curtain rod carrier having a bifurcated upper portion and a stem which extends therefrom to maintain the curtain rod carrier in a vertical position when engaging the socket, and a bend between the part of the curtain rod carrier that engages the socket and its bifurcated upper portion, said bend offsetting the bifurcated upper portion from the stem and tending to press 120 125 130

the part above the bend toward a surface to which the support is attached.

3. In a curtain and shade fixture, a support for attachment to a window frame, a curtain pole carrier maintained by the support the same having at its upper portion tines to provide a crotch for the reception of a curtain pole, the stem of said carrier

being bent transversely to cause in use the crotch portion of the carrier to be pressed 10 toward the window frame, for use with a curtain pole having ends provided with a flange or plate against which the tines of the carrier will abut to maintain the pole in a horizontal position.

MARY BORGES.
